TOOTHPICK

Ruth D. Simmons, Los Angeles, Calif.

Application April 19, 1954, Serial No. 30,088

Term of patent 14 years

(Cl. D86—10)

To all whom it may concern:

Be it known that I, Ruth D. Simmons, of Los Angeles, California, have invented a new, original, and ornamental Design for Toothpick of which the following is a specification, reference being had to the accompanying drawing, forming a part hereof. The present application is a continuation-in-part application of my co-pending application Serial No. D-26,973, filed on September 28, 1953, which is a divisional application of my co-pending application, Serial No. D-22,695, filed on December 13, 1952.

Figure 1 is a side elevational view of a toothpick showing my new design;

Figure 2 is a top view of the toothpick in Figure 1;

Figure 3 is an end view along lines 3—3 of Figure 1;

Figure 4 is a cross sectional view along section line 4—4 of Figure 3; and

Figure 5 is a cross sectional view along section line 5—5 of Figure 1.

I claim:

The ornamental design for a toothpick, substantially as shown.
